UNITED STATES PATENT OFFICE.

ESTEBAN MONEGAL PRAT, OF BARCELONA, SPAIN, ASSIGNOR TO MYRURGIA, S. A., OF BARCELONA, SPAIN.

DESIGN FOR A PERFUME BOTTLE CONTAINER.

Application filed November 24, 1926, Serial No. 19,836, and in Spain June 23, 1926. Term of patent 7 years.

To all whom it may concern:

Be it known that I, ESTEBAN MONEGAL PRAT, a subject of the King of Spain, residing at Barcelona, Spain, Consejo de Ciento 239, have invented a new, original, and ornamental Design for Perfume Bottle Container, of which the following is a specification, reference being had to the accompanying drawing, forming part thereof.

The figure is a front elevation of a perfume bottle container showing my new design.

I claim:

The ornamental design for a perfume bottle container as shown.

ESTEBAN MONEGAL PRAT.
